CLAIM

The ornamental design for the power connector, as shown and described.

DESCRIPTION

FIG. 1 is an isometric view of a power connector showing the new design.

FIG. 2 is a front elevational view thereof.

FIG. 3 is a rear elevational view thereof.

FIG. 4 is a right-side elevational view thereof. The left side elevation view is a mirror image of the right-side elevational view.

FIG. 5 is a top plan view thereof; and,

FIG. 6 is a bottom plan view thereof.

The broken lines in the drawings illustrate portions of the power connector that form no part of the claimed design.
